SANDGLASS TIMER

Walter Koch, 75 Glen Ridge Parkway,
Glen Ridge, N.J. 07028

Filed July 14, 1965, Ser. No. 86,157

Claims priority, application Japan Apr. 27, 1965

Term of patent 14 years

(Cl. D42—7)

Fig. 2

Fig. 1

Fig. 3

Fig. 6

Fig. 5

Fig. 7

Fig. 4

Fig. 8

FIGURE 1 is a left-end elevational view of a sandglass timer showing my new design;

FIGURE 2 is a front elevational view thereof;

FIGURE 3 is a right end elevational view thereof;

FIGURE 4 is a top plan view thereof;

FIGURE 5 is a bottom plan view thereof;

FIGURE 6 is a rear elevational view thereof;

FIGURE 7 is a perspective view thereof; and

FIGURE 8 is a sectional view thereof taken on line 8-8 of FIGURE 5.

The drawing is lined to indicate contrasting colors of materials in the sandglasses.

I claim:

The ornamental design for a sandglass timer, substantially as shown and described.
